UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO.

SEMAUTOMATIC TABLE-MOVING ATTACHMENT FOR PRESSES.

Application filed November 19, 1921. Serial No. 516,509.

To all whom it may concern:

Be it known that I, FRANCIS E. STEVENSON, a citizen of the United States, residing at Mount Gilead, in the county of Morrow and State of Ohio, have invented certain new and useful Improvements in Semiautomatic Table-Moving Attachments for Presses, of which the following is a specification.

This invention relates to a device for use with the work carrying table of a hydraulic or other press, whereby said table may be moved to and from an operative position by means which is started by the operator, but is automatically stopped at the termination of each movement whether this is from operative to inoperative position of said table or vice versa.

There is employed a rotary member between which and a source of power an operative connection may be manually effected at will, and connections between said rotary member and the work carrying table whereby the rotary movement of the member is converted into a reciprocatory movement of the table.

More specifically these connections comprise a crank head mounted to rotate both with and on said rotary member and a link capable of longitudinal and rotary movement connecting the crank head and the work carrying table.

Detent means, specifically a toggle lock, is provided for holding the parts in operative position after being manually set, and the rotary member carries means for automatically breaking said toggle lock at the termination of a predetermined movement of the rotary member.

In the accompanying drawings, Figure 1 is a top plan view, with parts in section;

Figure 2 is a vertical section;

Figure 3 is a top plan view of the attachment on a larger scale;

Figure 4 is a vertical view of the parts shown in Fig. 3, also on a larger scale;

Figures 5, 6, 7, 8 and 9 are plan views, somewhat diagrammatic in character, showing successive steps in the movement of parts of the device as the table is moved from operative to inoperative position.

The particular type of press to which this attachment is applied forms no part of the

invention and there is illustrated only generally an upper member 1 and a platen member 2.

The work carrying table 3 which is adapted to be reciprocated to a position between said press members, and to another position entirely free thereon, has a slot 4 along one edge in which engages a roller 5 on a pin 6 carried by the end of an arm 7. This table travels on rollers 8 carried by the platen member, and rollers 9 attached to the housing 10, which contains the operating mechanism for the table 3.

A pin 11 is rigidly mounted in a hub 12 carried by the housing 10, and keyed or otherwise fixed to said pin is a stationary gear 13. Meshing with the gear 13 is a gear 14 keyed or otherwise attached to a crank-head 15 so that they rotate in unison upon a pin 16 rigidly held in a plate 17 which rotates upon the pin 11 beneath the fixed gear 13. The crank-head 15 carries a pin 18 to which is attached the end of the arm 7. This arm has a slot 19 which engages a roller 20 on the upper end of the pin 11.

It is thus seen that the pin 16, gear 14, crank-head 15, and pin 18, with attached end 20 of the arm 7 all rotate about the pin 11.

Keyed or otherwise rigidly attached to the plate 17 is a worm wheel 21. Located adjacent said worm wheel is a shaft 22 mounted in two bearings 23 and 24. The bearing 23 is in the form of a U-joint, having two projecting pins 25, only one of which is shown, engaging in suitable bearings. The bearing 24 is of similar character, having pins 26 held by forked projections on the bar 27, which is slidably mounted in the housing 10. The shaft 22 carries a worm 28, normally disengaged from the worm gear 21.

Rigidly attached to the bar 27 is a rod 29 provided with a handle 30. A spring 31 is coiled about the rod 29 and held between the front of the housing 10 and nuts 32 on said rod, and normally holds the parts in the dotted line position shown in Figure 2.

A link 33 is pivoted at 34 to the housing 10, and at its other end at 36 to one arm of a bell-crank member 35, which is in turn pivoted to the bar 27 at 37. The link 33 and said arm of the bell-crank form a toggle member.

On the rotating plate 17 are pins 38, one

of which engages the upwardly extending arm of the bell-crank member 35, at the end of each half revolution of the plate 17.

Motion is transmitted to the shaft 22 from any suitable source of power in any desired manner, for example, by a pulley 39 and a belt 40.

The operation of the device is as follows:

Assuming the parts to be in the position shown in Figures 3, 4 and 5, at which time the table 3 is in operative relation to the press members, the operator pulls out the handle 30 from the normal position shown in full lines in these figures and by dotted lines in Figure 2, to the full line position of Figures 1 and 2. This moves the link 33 and bell-crank member 35 from the Figure 4 to the Figure 2 position, thus straightening the toggle and retaining the handle 30 in its operated position.

The operation of the handle has moved the bearing 24 of the shaft 22 to such an extent that the worm 28 is moved into engagement with the worm gear 21. The motion of the worm is therefore transmitted to the gear 21 and produces a rotary movement of the plate 17. Since this plate 17 carries the pin 16, said pin together with the gear 14, the crank-head 15, and the pin 18 carried thereby, are all given a rotary movement about the pin 11. The end of the arm 7, which is attached to the pin 18, also has a rotary movement. Furthermore, as the gear 14 meshes with the fixed gear 13, said gear and crank-head 15 have an additional movement of rotation about the pin 16 upon the plate 17.

One end of the arm 7 accordingly rotates about the pin 16, and with the pin 16 about the pin 11. The arm is permitted to move in the path necessitated by this double movement because of the slot 19 and because the opposite end of the arm may travel along the slot 4 in the table 3.

Successive steps in the operating movements are shown in Figures 5, 6, 7, 8 and 9. The gear 13 has just twice as many teeth as the gear 14, so that a half revolution of the plate 17 will result in a full revolution of the gear 14 and crank-head 15. When one-quarter of the movement of the plate 17 has taken place, the gear 14 and crank-head 15 have moved through a half revolution, or from the Figure 5 to the Figure 7 position.

When the plate 17 has completed a half revolution, the parts will have arrived at the Figure 9 position. At this time, one of the pins 38 has engaged the upper arm of the bell-crank 35 as indicated in Figure 2, and by its pressure thereagainst breaks the toggle formed by the other arm of the bell-crank and the link 33 and permits the spring 31 to return the bar 27 and shaft-bearing 24 to the position shown in Figure 3, thus disengaging the worm from the worm gear, and

stopping the rotary movement of the plate 17 and connected parts.

When it is desired to move the table into operative position, the handle 30 is operated again, and the resulting movement brings the parts from the position shown in Figure 9 to that of Figure 5, thus moving the table in the opposite direction.

The table has a free movement as it overlies the parts of the operating mechanism. The roller 5 moved in the path of an approximate ellipse during a complete rotation of the plate 17, and this permits the use of a narrow table and housing.

The device is semi-automatic in its operation, since it needs only to be started, and stops automatically at the end of the desired movement.

The invention is not limited in its application to any specific form of press, but may be used to supply work to machines of different types whenever a movement of the character described is necessary or desirable.

I claim as my invention:

1. In a device of the class described, a reciprocating table, an arm connected to said table, a housing, a pin rigidly mounted therein, said arm having a slot engaging said pin and means for giving said arm a longitudinal movement and a rotary movement about said pin, thereby reciprocating said table.

2. In a device of the class described, a reciprocating table, an arm connected to said table by a pin and groove connection, a housing, a pin fixedly mounted therein, said arm having a slot engaging said fixed pin, and means for giving said arm a combined longitudinal and rotary movement about said fixed pin, thereby reciprocating said table.

3. In a device of the class described, a reciprocating table, an arm connected to said table to move with and relatively thereto, a fixed pin, a slot in said arm engaging said pin, and means for giving said arm a combined longitudinal and rotary movement about said pin, thereby reciprocating said table.

4. In a device of the class described, a reciprocating table, an arm connected thereto at one end, a fixed pin, a slot in said arm engaging said pin, a plate rotating on said pin, a crank-head carried by said plate and also rotating thereon, said arm connected at its other end to said crank-head, and means for rotating said plate, whereby the arm is given a combined longitudinal and rotary movement about said pin and the table is reciprocated.

5. In a device of the class described, a reciprocating table, an arm connected therewith, a fixed pin, means for guiding said arm on said pin, means for giving said arm a longitudinal and rotary movement

about said pin, and means for automatically stopping the movement when said arm has moved through one half a revolution.

6. In a device of the class described, a reciprocating table, a housing adjacent thereto, a fixed pin mounted in said housing, a plate rotatable about said pin, and means carried by said plate and connected to said table whereby a rotary movement of the 10 plate is converted into a reciprocatory movement of said table.

7. In a device of the class described, a table movable from one rest position to another, a housing adjacent thereto, a fixed pin 15 in said housing, a plate rotatable about said pin, and means connecting the plate and table whereby each half rotation of the plate moves the table from one rest position to the other.

20 8. In a device of the class described, a reciprocating table, a housing adjacent thereto, a fixed pin in said housing, a fixed gear on said pin, a plate rotating about said pin, a crank-head rotatably mounted on said 25 plate, a gear rotating with said crank-head and meshing with said fixed gear, an arm guided by said pin and fixed at its ends to the crank-head and table respectively, whereby rotary movement of said plate is 30 converted into reciprocatory movement of the table.

9. In a device of the class described, a reciprocating table, a housing, a fixed pin therein, a fixed gear on said pin, a plate and 35 connected worm gear rotatable about said pin, a crank-head rotatably mounted on said plate, a gear rotating therewith and meshing with the fixed gear, an arm guided by said pin and connected at its ends to the 40 crank-head and table respectively, a source of power, and means for connecting the same to said worm gear, whereby the table is given a reciprocatory movement.

10. In a device of the class described, a table movable from one rest position to another, a support, a fixed pin thereon, a fixed gear on said pin, a plate rotatable on said pin, a crank-head rotatably mounted on said plate, a gear rigidly connected to said crank-head and meshing with said fixed gear, but 45 having one half the number of teeth, and means connecting the crank-head to the table, whereby a complete rotation of the crank-head is produced by half a rotation of the plate, and the table is thereby moved 50 from one rest position to the other.

11. In a device of the class described, a work carrying member, a rotatable plate, an axle about which said plate rotates, a fixed gear on said axle, a crank-head rotatably mounted on said plate, a gear rigid therewith which meshes with said fixed gear, and means connecting said crank-head with the work carrying member whereby rotary 55 movement of the plate results in a reciprocatory movement of the work carrying member.

12. In a device of the class described, a work carrying member, a housing, a fixed axle in said housing, a fixed gear on said 60 axle, a plate and rotatable gear mounted on said axle, means normally disconnected therefrom but movable into engagement with said rotary gear to impart motion thereto, a crank-head and associated gear 65 mounted on said plate and meshing with said fixed gear, whereby said crank-head rotates with and on said plate, a link guided in longitudinal motion by said axle and connecting the crank-head and work carrying member, whereby rotation of the table is 70 converted into reciprocatory movement of the work carrying member.

In testimony whereof, I have hereunto 75 subscribed my name.

FRANCIS E. STEVENSON.
